INVENTOR.
Edward H. Beardsley
Wm. G. Vanderlip.

ATTORNEY.

UNITED STATES PATENT OFFICE.

EDWARD H. BEARDSLEY, OF ELKHART, INDIANA.

PAD PRESSES FOR WIND MUSICAL INSTRUMENTS.

Application filed February 20, 1924. Serial No. 694,160.

To all whom it may concern:

Be it known that I, EDWARD H. BEARDSLEY, a citizen of the United States, and a resident of Elkhart, county of Elkhart, and State of Indiana, have invented certain new and useful Improvements in Pad Presses for Wind Musical Instruments, of which the following is a specification.

This invention relates to wind musical instruments, and especially to instruments of the saxophone class in which yieldable valve pads are incorporated.

It is well known that saxophones have a plurality of valves each of which is provided with a yieldable pad adapted to engage the valve seat which encompasses the tone opening in the body of the instrument. It is also well known that saxophone valves normally are disengaged with the valve seat and that the valve pad must be brought into engagement with the valve seat to close the tone opening in order to produce a tone. The valve pad is usually made of felt and kid to seal the tone opening effectually when the valve is closed, and the sealing efficiency of the pad is materially enhanced when the pad is permanently creased or impressed by the valve seat, which crease can ordinarily be made only by extended use of the instrument. When the instrument is not in use and the valves stand open the kid facing of the valve pad either loses the crease altogether or becomes wrinkled or puckered to such an extent that, when the instrument is again used, the tones are deficient in quality or volume on account of the air leakage due to the imperfect seal made between the valve pad and valve seat.

To meet and overcome this defect it is necessary to again form a crease in the valve pad and this can be done only by actual use of the instrument.

The principal object of my invention is to produce a valve pad press to hold the pad against the valve seat when the instrument, of the saxophone class is not in use, in order to create a crease or impression in the valve pad or to maintain one already formed.

Other and more specific objects of the invention are mentioned and described herein.

The preferred embodiment of my invention is illustrated in the accompanying drawing in which Figure 1 is a view of a saxophone fragment showing a plurality of

valves confined on their seats by the invention; Fig. 2 is a transverse view in elevation, partially in section, showing the same elements; Fig. 3 is a slightly modified form 60 of my invention for application to another part of the instrument; Fig. 4 is a transverse view in elevation, partially in section, showing the same elements; Fig. 5 is a plan view of a fragment of the bell section of a 65 saxophone showing a single valve and another modification of the invention which is applied thereto to confine the valve on its seat; and Fig. 6 is a transverse view of the same members in elevation and partially in 70 section.

Similar numerals of reference indicate like parts throughout the several views on the drawing.

Referring to the details of the drawing, the numeral 1 indicates a fragment of the tubular main body portion of a saxophone of the usual type, the numeral 2 indicates a fragment of the belled portion of the instrument which is connected with body portion 80 1 by a return bend—not shown—as is well known in the art.

A saxophone is provided with a plurality of tone openings of various sizes which are controlled by spring controlled padded 85 valves which normally stand open and are adapted for manipulation to close said tone openings for the tone production.

On the drawing, the numerals 3, 4 and 5 indicate three valves (Figures 1 and 2) 90 adapted to close the tone openings 6, 7 and 8, respectively, formed in the body 1, said valves being mounted for oscillation upon a shaft 9 carried on the instrument in suitable bearings—not shown—which are well known 95 in the art. Each tone opening is encompassed by the laterally projecting annular flange 10 which may be integral with body 1, or otherwise formed. Each valve 3, 4 and 5 is provided with a felt pad 5' and each is 100 closed by manipulation of the finger tip 11 which is operatively connected with the shaft 9. Each tone opening 6, 7 and 8 is adapted to be closed and sealed by the yieldable pad 5', usually made of felt and faced 105 with kid, which engages the edge of the tone opening flange 10 and which is impressed thereby. Fig. 2. Adjacent shaft 9 and substantially parallel therewith a second valve shaft 12 is mounted for rotation in suitable 110 bearings, which shaft controls another valve or set of valves—not shown—and which

may be closed by manipulation of the finger tip or key 13 connected with shaft 12 by the arm 14. At another portion of the instrument the three padded valves 15, 16 and 17 are located and adapted to close corresponding tone openings, each of which openings is encompassed by the flange 18 to serve as a seat for the valve pads.

10 The valves 15, 16 and 17 are mounted upon a rotary shaft 19 carried by the instrument in suitable bearings—not shown—which shaft is arranged between the instrument portions 1 and 2 (Fig. 4) and is manipulated in the usual manner to operate 15 said valves for closure thereof. A shaft 20 terminates on the opposite side of the instrument section 1 and may be mounted in the post 21. Adjacent shaft 19 another shaft 39 is mounted for rotation by a finger 20 tip or key 40 which is disposed above the valve 16 and connected with said shaft by an arm 41, said shaft 39 being adapted to close a valve, or valves, not shown on the drawing.

25 The numeral 42 indicates a shaft mounted upon the instrument substantially opposite shaft 12 for the actuation of a valve—not shown—and which is to be used as an anchorage, as hereinafter described.

30 At a third position on the instrument and adjacent the bend thereof, a padded valve 22 is provided and adapted to close the tone opening 23 when seated upon the annular seat 24, which valve is normally a single unit 35 and may be actuated by an arm 25 connected with a rotary shaft—not shown—in any suitable manner. On account of the exposed position of the valve 22 a guard 26 is disposed above the valve and spaced therefrom 40 to permit the outward swing thereof when disengaged with its seat, said guard serving also as a stop for said valve, as is well known.

45 To obtain the best tones from an instrument of the saxophone type it is necessary to form and maintain a crease or impression in the yieldable pad 5' which crease can be made only by the edge of the valve seat when the valve pad is pressed against it. When the instrument is not in use regularly the valve pad crease disappears or becomes shallow, or the pad kid may wrinkle or warp, whereby the pad becomes an inefficient sealing element, thereby materially 50 affecting the tones produced when the instrument is in use.

55 My invention contemplates means for closing the various valves of the instrument to press the valve pad into close engagement with the valve seat to form a crease or impression in the pad, or to maintain a crease already formed, thereby insuring the immediate production of the best tones when used after extended disuse of the instrument. Of this pad press means two are

substantially similar, and the third one is particularly applicable to the valve 22, or any other single unit valve, and somewhat different in construction from the others, but accomplishing the same result.

70 The numerals 27 and 28 indicate generally two valve pad press elements adapted to be detachably secured to the instrument to close the valves 3, 4 and 5, and valves 15, 16 and 17, respectively, for the purpose described. Each press element 27 and 28 may include a tubular body 29, a lateral arm 30 provided with an integral hook 31, and, opposed to hook 31, a second hook 32 which is connected with the stub arm 33 by a coil 75 spring 34. Each element 27 and 28 may be provided also with the end pads 35 and 36 mounted upon the shaft or arm 37 which is slidably and rotatably mounted within the tubular body 29 to enable extensibility and adjustability of said pads, as hereinafter described. Each of the tips or pads 36 and 35 may be provided with a cork face element 38, secured thereto in any suitable manner, to prevent abrasion of the valve body when the latter is engaged thereby, as hereinafter mentioned.

80 The arm 30 of element 27 may have a leaf spring 43 secured on its under side to function as hereinafter described. A third pad 85 press element 44 may be used to engage the single valve 22 and may comprise a leaf spring plate 45 provided with a cupped portion 47 to carry the cork pad 46 centrally of one side thereof, and a pair of cork pads 100 48, 48 at opposite ends of the opposite side of said plate, said corks being mounted in cups 49 rigid with said plate portion.

85 In operation, element 44 functions as follows: The valve 22 is first closed to press 105 the pad thereof against the valve seat. Thereupon, the spring plate 45 is forced beneath the guard 26, whereby pads 48 engage the under side of the guard 26 and pad 46 engages the outer face of the valve 22, thereby resiliently confining the valve pad of said valve in close engagement with the valve seat.

90 In the application of press element 27 to the instrument the hook 31 is caused to engage beneath the shaft 12 to position the arm 30 above finger tip 11 and pads 35 and 36 in light engagement with finger tip 13 and valve 3, respectively, in which relation of the parts the body 29 extends across the valve 4 and the spring 43 engages and bears against tip 11. The spring 34 is then extended by drawing the hook 32 downward into engagement with the shaft 42, whereby valves 3, 4 and 5 are seated by direct application of the press, and also the valve, or valves, actuated by shaft 12 when the key or tip 13 is depressed by pad 35.

95 In applying press element 28 the hook 31 thereof, which conforms to the contour of 130

the instrument portion 2, is thrust beneath the latter to place the pads 35 and 36 in engagement with the valves 15 and 17, the body portion 29 engaging the key 40. 5 Thereafter, hook 32 is engaged with shaft 20 by extension of the spring 34 to apply the press to said parts with force, whereby the valves 15, 16 and 17 are firmly seated, and the shaft 39 actuated by the depression of 10 the key 40 which in turn closes the valve, or valves, connected with and actuated by the movement of the shaft 39, as described. The extensibility of the pad arms 37 enables the application of the press devices 27 and 15 28 to various sizes of saxophones in which the valve centers may vary.

I claim as my invention.

1. An attachment for musical wind instruments including tone openings and 20 valves, comprising an attaching element engageable with portions of the musical instrument to maintain the attachment in position thereon, and means carried by the attaching element for maintaining the valves 25 of the musical instrument in closed position.

2. An attachment for wind musical instruments including tone openings and normally open valves associated with said openings, comprising an attaching element engageable with portions of the musical instrument whereby to maintain the attachment in position thereon, and resilient members engageable with the valves of the musical instrument whereby to maintain the latter in closed position. 30

3. An attachment as claimed in claim 2 characterized by the provision of means for

resiliently pressing the attaching element to maintain the valves in closed position. 40

4. An attachment for wind musical instruments of the type including tone openings and normally open valves associated therewith, comprising an attaching element engageable with portions of the musical instrument to maintain the attachment in position thereon, and relatively adjustable 45 valve engaging members adapted to engage and maintain the valve of the musical instrument in closed position.

5. An attachment as claimed in claim 4 characterized in that the attaching element includes spring means normally acting to resiliently press the valve engaging members in engagement with the valves. 50

6. An attachment for wind musical instruments of the type including tone openings, valves associated with the openings and finger pieces associated with the valves whereby to close the latter, comprising an attaching element engageable with portions 60 of the musical instrument whereby to maintain the attachment in position thereon, relatively adjustable valve engaging members carried by the attaching element for engaging and maintaining the valves of the musical instruments in closed position, and means carried by the attaching element for engaging and operating certain of the finger pieces whereby to move the valve associated therewith into closed position. 65 70

In witness whereof I have hereunto affixed my signature this 18th day of February, 1924.

EDWARD H. BEARDSLEY.
